POLYFORM CONVERSION OF HYDRO-CARBONS

August Henry Schutte, Hastings on Hudson, N. Y.,
assignor to The Lummus Company, New York,
N. Y., a corporation of Delaware

Application May 1, 1943, Serial No. 485,286

3 Claims. (Cl. 196—9)

This invention relates to improvements in the conversion of hydrocarbons for the production of lower boiling materials, particularly those in the gasoline range; and it specifically relates to an improved method for obtaining a higher crack per pass in the combined conversion of normally liquid hydrocarbon cracking stocks and normally gaseous hydrocarbons.

It has been established that the simultaneous conversion of the normally gaseous C₃ and C₄ hydrocarbons and of a normally liquid cracking stock permits an increase in the cracking temperature over that permissible in conventional thermal cracking so that an average crack per pass of approximately 22% is obtained as compared to the usual average of 16%. With this higher crack per pass, which is produced by the use of the higher operating temperatures, the total amount of oil circulation to the cracking heater is less than that in conventional thermal cracking for a given amount of charge stock. At the same time, the total amount of oil vapors to be handled in the tower fractionating system is correspondingly reduced. The decrease in the total amount of oil circulation to the heater, however, is partially or wholly offset by an increase in the total amount of heater throughput because of the introduction of the C₃ and C₄ hydrocarbons along with the cracking charge stock. The total amount of heater charge, which comprises the oil and the gas, is, therefore, approximately the same as the total amount of heater charge in conventional thermal cracking; but, because of the higher cracking temperature permissible, the gasoline octane number is considerably higher than that obtained by conventional thermal methods. The loss in gasoline yield, which would normally be expected when a higher crack per pass and a higher octane number are realized, is made up for by polymerization of C₃ and C₄ hydrocarbons.

In thermal cracking operations as well as in the combined gas-liquid cracking or polyforming operations, the formation of coke is a limiting factor with respect to the temperature at which the cracking heater may be operated for any commercially suitable period. The time-temperature relation must be so adjusted as to produce an efficient conversion of the charge stock just short of coke formation. The higher permissible operating temperature obtained in the polyforming operation, whereby a higher yield per pass of gasoline is produced, results from the fact that the C₃ and C₄ hydrocarbons introduced with the charge oil into the heater lower the pseudocritical temperature of the ma-

terial in the heater tubes or coil and permit the formation of more and heavier tarry and polymeric coke-forming materials before such materials are deposited as a liquid phase in the tubes and coking difficulty sets in. Because of this coke formation, the gas-oil cracking mixture is subjected to polyforming conditions only until the pseudocritical temperature of the coil material approaches the temperature of operation and there is danger of separation of a liquid phase, at which point the coil material is quenched to arrest the cracking reaction and the tendency to form coke.

The principal object of my invention is to provide an improved process for the simultaneous conversion of normally gaseous and normally liquid hydrocarbons whereby the crack per pass may be materially increased without any substantial shortening of the operating period.

Another object of my invention is to conduct this improved process so that the total amount of heater charge, the total amount of material processed in the tower system, and the total amount of heat to be recovered by heat exchange are materially reduced.

A further object of my invention is to increase the overall octane number of the gasoline obtained in the polyforming operation.

Further objects and advantages of my invention will be apparent from the following description thereof, taken in connection with the attached drawing, which shows a flow sheet of a combination cracking system embodying the features of my invention.

As the polyform process is now carried out, a suitable cracking stock in admixture with a sufficient quantity of hydrocarbon gases, primarily those having 3 to 4 carbon atoms per molecule, is passed through a conversion zone under conditions more drastic than those to which the cracking stock alone could be subjected without coking. As already pointed out, these gases serve to lower the pseudocritical temperature of the mixture so that a higher conversion temperature can be employed before tar deposition and accompanying coke formation take place. The hydrocarbons are subjected to the conversion conditions until the incipient coking stage or the coking threshold is reached, at which point they are cooled by the addition of a quenching oil which serves to arrest the conversion reactions. The cooled hydrocarbons are then fractionated under reduced pressure for the separation of the particular cracked fractions desired. Because of the coke-forming tendency of the heavy polymeric and tar-forming constit-

uents developed during the period of conversion, the degree of conversion per pass possible is definitely limited; and a particular cracking stock is subjected only to a single-stage treatment.

By means of my improved process, the initial charging stock may be subjected to two or more conversion stages maintained at progressively increasing temperatures without the operating limitation imposed by the formation of coke in the conversion zone as the temperature is increased. According to my invention, a suitable cracking stock, ranging in type from naphtha to reduced crude, is commingled with normally gaseous hydrocarbons having from 3 to 4 carbon atoms per molecule, and the mixture is then passed through a first conversion stage wherein it is subjected to conversion conditions until the point of incipient coking or the coking threshold is reached. The partly converted hydrocarbons are then withdrawn from the conversion stage and cooled, preferably by the addition of a suitable quenching oil, in order to arrest the conversion reactions and to separate out the heavy polymeric and tar-forming constituents in a liquid phase. During such step, the conditions are so adjusted that substantially none or, at the most, only a very small percentage of the light, nontarry constituents is transferred into the liquid phase. The remaining vaporous constituents, to which additional normally gaseous C₃ and C₄ hydrocarbons may first be added, are then passed through a second conversion stage wherein they are subjected to a higher conversion temperature than that maintained in the first stage.

Again in the second stage the conversion is carried out until the coking threshold is reached, at which point the reacting hydrocarbons are withdrawn and are cooled to separate out additional tarry constituents as a liquid phase. The remaining vapors may then be subjected to treatment in further conversion stages, the number of which is limited only by the pressure on the hydrocarbons entering the initial conversion stage and the pressure drop through each conversion stage in the system. The various products of conversion are then fractionated into normally gaseous constituents, gasoline, a fuel oil residuum, and an intermediate cycle cracking stock. The C₃ and C₄ gases, from which those hydrocarbons having 2 or less carbon atoms per molecule have been first removed, are preferably recycled for admixture with the cracking stock as hereinbefore indicated; and the intermediate cycle cracking stock may be combined with the cracking charge stock.

Although any desired number of conversion stages may be employed, for convenience only the description of my invention will be limited to a process embodying only three stages.

My process is applicable to the conversion of various types of hydrocarbon stocks not suitable for use as a motor fuel into gasoline having an exceptionally high octane rating. It may be equally applied to the reforming of heavy naphtha, to the cracking of gas oil, and to the viscosity-breaking of residual material. The process is particularly adapted for use in conjunction with a combination unit wherein all the cracking stocks are simultaneously but independently treated.

The increased yield of gasoline per pass obtained by my improved process requires a smaller total amount of heater charge than that in the

customary polyform operation for a given production of gasoline. As a result of the increased gasoline yield, the recycle streams of cracking stock and hydrocarbon gases are materially reduced in amount. The advantages of such operation are that the cracking heater duties are decreased, the necessary fractionating equipment is smaller, and the required heat exchange surface for heat recovery is less.

In one embodiment of my process, a heavy gas oil in admixture with C₃ and C₄ hydrocarbons is introduced into a heater and subjected to cracking conditions, as in the case of polyforming, up to the coking threshold, i. e., up to the point where the pseudocritical temperature of the coil material approaches the operating temperature and there is danger of separation of a liquid phase. When this point is reached, the coil material, instead of being quenched and introduced into a tower system under reduced pressure, is removed from the heater and cooled only sufficiently at full pressure to separate out a liquid phase containing the heavy tar and polymers and as small an amount of lighter constituents as possible. The separated liquid phase is withdrawn to the tower system for fractionation into fuel oil, cycle gas oil, gasoline, and gas. The vapors recovered from the initial separation constitute a clean cracking stock and are subjected to further pyrolysis with further addition of C₃ and C₄ hydrocarbons, if desired, but without intermediate fractionation. In this fashion a 25° A. P. I. gas oil, which had a 50% point of 700° F. and could be cracked to give only about a 16% crack per pass by conventional methods or about a 22% crack per pass by the polyform process, can be processed to yield up to 35% gasoline per pass.

One application of this principle to a combination cracking unit is shown in the accompanying drawing. In this case a fresh heavy gas oil charge stock is introduced by pump 10 through line 11 into the gas oil coil or heater 12. This charge may be augmented by a cycle gas oil introduced through line 13. C₃ and C₄ hydrocarbons from line 15 are added to the gas oil charge stock to provide the desired polyform charge mixture. The quantity of these gaseous hydrocarbons is so controlled as to give the proper gas-oil ratio for the desired pseudocritical temperature of the mixture flowing through the heater and usually amounts to 50 to 75% by volume on the oil. The conversion in heater 12 is carried on to the greatest extent and for the longest time permitted by coke formation at the particular operating temperature and pressure employed, which may range from about 950 to 990° F. and from about 600 to 1500 pounds per square inch, respectively. The partially converted material is then discharged from the heater and quenched sufficiently by admixture with a suitable quench oil introduced through line 16 to condense the undesired heavy tarry constituents present therein. The quenched mixture is passed to separator 17, from which the separated liquid is withdrawn through line 18 under control of liquid level control 19 and valve 20. The remaining vapors are removed from separator 17 through line 21 for further treatment as hereinafter described.

The amount of quench oil used is so regulated as to condense only the heavy tarry, coke-forming constituents present in the effluent mixture from coil 12. Condensation of the nontarry components of this mixture is to be particularly avoided; for these components are to be sub-

jected to further conversion in accordance with my invention. At the same time, removal of all the tarry, coke-forming constituents from the remaining vapors is essential to avoid deposition of coke in the subsequent conversion stages. Hence, control of the temperature to which the partially converted mixture is cooled is of utmost importance in the efficient operation of my process. The separation obtained in separator 17 may be controlled and modified not only by the temperature to which the coil effluent material is cooled but also to a considerable degree by the amount of C₃ and C₄ hydrocarbons initially admixed with the charge to coil 12 by reason of the partial pressure effect exerted by these gaseous hydrocarbons.

A further quantity of C₃ and C₄ hydrocarbons may be added through line 22 to the separated vapors before introduction thereof into the second coil or heater 23 if such addition is desirable. The conversion is then continued in heater 23, until the coking threshold is again approached, at a temperature ranging from about 980° to 1000° F. and a pressure ranging from about 500 to 1400 pounds per square inch. Quench oil from line 25 is then admixed with the effluent from heater 23 in the same manner as described above, and the cooled mixture is introduced into separator 26. The separated liquid tarry material is drawn off through line 27 under control of valve 28 and liquid level control 29, and the separated vapors are withdrawn through line 30.

The separated vapors may again be subjected to further conversion in coil 31 under appropriate temperature and pressure conditions either alone or in admixture with further C₃ and C₄ hydrocarbons from line 32. As before, the conversion is carried out until the coking threshold is reached, at which point the effluent material from coil 31 is admixed with quench oil from line 34. The quenched stream is then introduced through line 35 into bubble tower 36 for separation into the desired products. This step-wise procedure may be repeated as many times as desirable. The only practical operating limitation is that the pressure in the final cracking coil should not drop below the minimum economic pressure for recycle gas oil cracking.

When this last stage is reached, accordingly, reduced crude from any convenient source is desirably introduced through lines 37 and 38 by means of pump 39 into the vapors and gases in line 30, and the mixture is passed to cracking coil 31. In such case, sufficient C₃ and C₄ hydrocarbons are added through line 32 to lower the pseudocritical temperature of the reduced crude to the desired degree; and the conversion in coil 31 is then conducted under lower pressure and temperature, for example, at a pressure ranging from about 300 to 500 pounds per square inch and a temperature ranging from about 850 to 950° F., to effect a viscosity-breaking of or a wax destruction in the reduced crude. The resulting effluent from coil 31 is then suitably quenched and introduced into tower 36 for the desired separation.

Alternatively, the reduced crude introduced through line 37 may be separately treated in heater 40 either alone or in admixture with C₃ and C₄ hydrocarbons from line 42 ranging in amount from about 50 to 100% by volume on the oil. The conditions in heater 40 are such that a viscosity-breaking of the reduced crude is primarily effected. The coil effluent is admixed with quench oil from line 34a, and the resulting

quenched stream is passed to bubble tower 36 through line 35 in admixture with the conversion products from heater 31.

In bubble tower 36, the cracked products are separated into an overhead consisting of unconverted C₃ and C₄ hydrocarbons and gasoline, which is removed through line 44, and a fuel oil bottoms consisting of the heaviest cracked material, which is withdrawn through line 45. An intermediate fraction comprising a cycle gas oil is collected on tray 46 and is removed through line 46a by means of pump 47 for admixture with the incoming gas oil charge in line 11. The liquid separated out in separators 17 and 26 is also passed through line 48 to the lower part of tower 36 for separation into the respective fractions.

The overhead from bubble tower 36 is passed to stabilizer 49, from which stabilized high octane gasoline is removed through bottoms line 50. The overhead from the stabilizer, consisting principally of C₃ and C₄ hydrocarbons as well as lighter hydrocarbons and hydrogen, is removed through line 52 and is partially condensed in condenser 53 to produce a C₃—C₄ condensate which is separated out in accumulator 54. A portion of this condensate is returned as reflux to the stabilizer 49 through line 55. The major portion of the liquefied C₃ and C₄ hydrocarbons is passed by pump 56 into line 57, which supplies the C₃ and C₄ hydrocarbons for the various heaters through the branch lines 15, 22, 32, and 42. The balance of this condensate may be passed through line 58 into the bottom of absorber 59, into which the uncondensed C₃ and C₄ hydrocarbon mixture from accumulator 54 is also introduced through line 60.

In absorber 59, the gaseous hydrocarbons are contacted with naphtha introduced through line 62 to absorb the C₃ and C₄ components therefrom. Additional C₃ and C₄ stock may be introduced into the system through line 63. The enriched naphtha is removed through bottoms line 64, and the stripped gases are discharged through line 65. This enriched naphtha together with additional naphtha, if desired, introduced through line 66, is then preferably passed by means of pump 66a through the heater 67, wherein the conditions are such that a reforming of the naphtha and a polymerizing of the gases into high octane gasoline take place. The effluent from coil 67 is passed through line 68 to bubble tower 36 for separation into the desired fractions. The C₃ and C₄ hydrocarbons present in the naphtha charge may range in amount from about 100 to 150% by volume on the naphtha, and the pressure in coil 67 may range from about 1000 to 2000 pounds per square inch with a temperature ranging from about 1020 to 1100° F.

The quench oil for the gas oil coils may be derived from several sources. A portion of the cycle gas oil in line 46a may be passed through line 70 into the separate lines 16, 25, 34, and 34a leading to the outlet lines from the respective heaters. Alternatively, a suitable gas oil from an external source may be introduced through line 72 for this purpose. A portion of this gas oil from line 72 may also be introduced with the cycle gas oil through line 13 into the gas oil coil 12. In addition, a portion of the fuel oil in line 45 may be diverted through line 74 by means of pump 75 for use as the quench oil.

Because a higher crack per pass is obtained by interstage separation and elimination of the heavy tarry polymers from the heater stream, a

lower overall heater charge is obtained. Since the amount of C₃ and C₄ hydrocarbons necessary in the conversion reaction is in direct ratio to the amount of oil processed, the quantity of this material is likewise reduced. Because a higher crack per pass is obtained, there is slightly more gas production from the gas oil and reduced crude conversion in the present system than is normally the case in conventional polyforming. In spite of this feature, the overall gas charge to the heaters is considerably less than that in conventional combination polyforming.

The above description relates particularly to a combined process for simultaneously treating the reduced crude, the gas oil, and the naphtha recovered in the distillation of a crude oil, which distillation can, of course, be conducted in a single primary still or fractionating tower (not shown). The naphtha recovered as a side stream from such tower can be fed to the above-described system through lines 62 and 66; the gas oil, also recovered as a side stream, can be fed through line 11; and the reduced crude removed from the bottom of such tower can be fed through line 31.

But the described system is also applicable to the treatment of these stocks individually with only slight modifications. If a gas oil or a reduced crude stock is treated alone, for example, it can be fed to heater 12 through line 11 as previously described. In this case the heater 40 and the line 31 are not used, and no feed of naphtha is required. Instead of feeding naphtha into the absorber 59 for absorption of the C₃ and C₄ hydrocarbons, a portion of the recycle gas oil, which is recovered from plate 46 in bubble tower 36, can be used. This gas oil can be passed by line 76 through a cooling unit 77 and then into the top of the absorber through line 62, and the enriched gas oil can be subjected to conversion either in a single-stage system or in a multi-stage system.

In one specific embodiment of this invention wherein a 25% A. P. I. gas oil having a mean boiling point of 700° F. was introduced through line 11, the total furnace charge amounted to only 240% on the fresh feed oil. This example demonstrates the important advantages gained by the present invention in comparison with the conventional polyforming process, in which a total furnace charge of approximately 415% would have been required for the same oil. In my process less heat is required, decreased tower diameters can be employed, less overall heat transfer surface is required, and higher yields of gasoline with a higher overall octane number are obtained.

While I have described what I consider to be the most advantageous modifications of my process, it will be evident to those skilled in this art that various other modifications can be made in the specific procedures set out without departing from the scope of this invention. Thus, it is possible to recover the C₃ and C₄ hydrocarbons in the gases leaving the stabilizer by other than absorption methods. And, as mentioned previously, it is possible to employ three or even more conversion stages, preferably operated at increasingly higher temperatures. It is also possible to employ centrifugal type separators in separators 17 and 26 if desired. Other modifications of my process which fall within the scope of the following claims will be immediately evident to those skilled in the art.

I claim:

1. In the cracking of hydrocarbons to obtain gasoline of high octane rating, the steps which

comprise mixing a gas oil with C₃ and C₄ hydrocarbons in proportions varying from about 50 to 75% based on the volume of the gas oil, passing the mixture through a conversion zone under a pressure of 600 to 1,500 lbs. per square inch and at a temperature of 950 to 990° F. until the incipient coking stage is reached, quenching the conversion products to separate out substantially only the heavy tar-forming constituents, mixing additional C₃ and C₄ hydrocarbons with the remaining vapors and passing the resulting mixture through a second conversion zone under a pressure of 500 to 1,400 lbs. per square inch and at a temperature of 980 to 1,000° F. until the incipient coking stage is again reached, quenching the conversion products to separate out additional heavy tar-forming constituents, combining the remaining vapors with additional C₃ and C₄ hydrocarbons and with a reduced crude, passing the resulting mixture through a third conversion zone under a pressure of 300 to 500 lbs. per square inch and at a temperature of 850 to 950° F. to effect a further conversion of the vapors to gasoline and a viscosity-breaking of the reduced crude, quenching the conversion products, introducing the quenched conversion products into a fractionating zone and therein separating out a heavy bottoms fraction, an intermediate cycle gas oil fraction and an overhead gasoline fraction containing C₃ and C₄ hydrocarbons, separating the C₃ and C₄ hydrocarbons from the gasoline overhead, and recycling such C₃ and C₄ hydrocarbons for admixture with the charges to the respective conversion zones.

2. In the process as claimed in claim 1, the steps of returning a portion of the intermediate cycle gas oil fraction for admixture with the initial gas oil charge and utilizing the remainder of the cycle gas oil fraction in the respective quenching steps.

3. In the cracking of a gas oil to obtain a gasoline of high octane rating, the process which comprises passing the gas oil in admixture with normally gaseous C₃ and C₄ hydrocarbons through a plurality of conversion zones maintained under superatmospheric pressure and at successively higher temperatures substantially higher than those which could be employed without undesirable coke formation in the absence of the gaseous hydrocarbons, mixing the conversion products from each conversion zone with a quench oil in a separating zone in quantity sufficient to separate out only the heavy tar-forming constituents as a liquid phase, introducing into the vapors remaining after each separation an additional quantity of C₃ and C₄ hydrocarbons and passing the resulting mixture into the next succeeding conversion zone, admixing the vapors from the final separating zone with a reduced crude and with additional C₃ and C₄ hydrocarbons and passing the mixture through a final conversion zone at a superatmospheric pressure and at a temperature lower than those employed in the previous conversion zones to effect further conversion of the vapors into gasoline, passing the products from the final conversion zone into a fractionating zone, recovering from the fractionating zone an overhead fraction containing gasoline and C₃ and C₄ hydrocarbons, separating the C₃ and C₄ hydrocarbons from said overhead fraction, and recycling them to be admixed with the hydrocarbon charges entering the successive conversion zones.
